ABSTRACT

A linear loading film processing device for developing an elongated strip of film, wherein the device includes a developer tube having end caps threadably secured thereto, a light trap formed inside the tube proximate one end thereof, and a film holding unit removably disposed in the tube wherein the film is disposed in a transversely arcuate configuration with only the longitudinal edges thereof in contact with the unit thus permitting developing fluid to contact both sides of the film.

FIG. 4

FIG. 5

FIG. 6

FIG. 7

LINEAR LOADING FILM PROCESSING DEVICE

BACKGROUND OF THE INVENTION

The art of developing rolls of film has generally involved the use of relatively large volume tanks containing developer solution, bath solution, fixer solution and water. The tanks are disposed in a dark room and the process of developing the film is substantially accomplished under controlled light conditions. Large quantities of expensive solutions are used and they must be replenished frequently because of aging and deterioration. The costs of equipment and solution thus have substantially restricted the development of film to the large commercial and professional developers. The average hobbyist and low volume commercial photographer must therefore send their film to others for development.

To overcome the disadvantage of cost and space a canister or sealable tank has been developed for the hobbyist and professional who has a low volume of development work. This canister comprises an elongated tank having a passage formed therethrough and which is sealable on both ends. The passage has a transverse or lateral configuration which is slightly smaller than the width of the film thus requiring that the film be bowed transversely. A plurality of spaced nodules are disposed along the inner top wall of the canister to prevent the film from contacting the top wall. Ports are provided in one end of the canister and are connected to a filling tube to permit charging and discharging the canister with solution. An environment having no light is thus provided for the development process. (Pat. No. 3,192,847, issued to S. H. Ener, July 6, 1965)

Several disadvantages are inherent in the above disclosed canister. For example, the loading of film is difficult because a roll of film is several feet long and extremely flexible. Furthermore the film must be loaded into the canister in only one way to provide that the emulsion side thereof does not contact any wall or nodule. The charging and discharging of the canister through the tube and ports takes considerable time and requires an extremely effective design of the device to permit complete discharging of the solution. Accidental removal of one of the ends subjects any film in the canister to light and thus causes exposure.

SUMMARY OF THE INVENTION

This invention relates to a novel linear loading film processing device for developing an elongated strip of film wherein the device includes a developer tube and a removable film strip holder. The tube has a chamber formed longitudinally therethrough of slightly greater dimensions than the holder thus minimizing the amount of solution required for the developing process. Each end of the tube is threadably capped to permit easy cleaning of the passage. A light trap element is disposed in the tube proximate one end thereof and a handle having a passage formed axially therethrough which fluidly communicates with the chamber thus facilitating the charging of the chamber. The passage communicates with the chamber on both sides of the light trap element and serves as an internal air vent to allow the smooth flow of the processing solutions through the light trap. The other end of the tube has no obstruction and thus facilitates the loading and unloading of the film strip holder.

The film strip holder is provided to permit the easy loading of the film thereon in a dark room. The holder is flanged and its transverse dimension is slightly smaller than the width of the film thus causing the film to bow slightly wherein it does not contact either the holder or the tube intermediate its edges. The solution can therefore contact both sides of the film thus permitting the emulsion side of the film to be loaded either facing toward or away from the holder.

The primary object of this invention is the provision of an extremely effective, economical and novel film processing device.

Another object of this invention is to provide a linear loading film processing device which uses a minimum volume of developing solutions, which assures no spillage of solution during agitation of the device, which is easily and smoothly charged and discharged with solution, which is substantially of one piece construction, which permits thorough agitation of the solution, which does not require that the developing process occur in a dark room except during the loading of the film strip into the holder and the loading of the holder into a processing chamber, which has a light trap element mounted in one end of the chamber, which has a handle mounted adjacent the light trap with a passage formed therein with the passage communicating with the chamber on both sides of the light trap to provide an internal air vent, which is threadably capped on both ends to allow the chamber to be easily cleaned, which because of its external configuration is easy to store, which provides a closed environment for the solution thus permitting the temperature of the solution to be retained at ideal values, which is easily transported and agitated because of the handle, and which can be readily formed from plastic or metal.

Yet another object of this invention is the provision of a film processing device wherein the film is easily and effectively mounted in a film strip holder which is removably disposable in a chamber which can be charged with a film developing solution.

A further object of this invention is to provide a linear loading film processing device which is economical of manufacture, simple and durable of construction, effective in service, which does not require exceptional training in its use, and which a hobbyist, an amateur, a low volume commercial photographer, or a child can effectively use.

These objects and other features and advantages of this invention will become readily apparent upon reference to the following description when taken in conjunction with the accompanying drawings.

BRIEF DESCRIPTION OF THE DRAWINGS

FIG. 1 is a perspective view of this invention;

FIG. 2 is an exploded top view thereof;

FIG. 3 is a sectional view taken along the lines 3-3 in FIG. 1;

FIG. 4 is a sectional view taken along the lines 4-4 in FIG. 1;

FIG. 5 is a sectional view taken along the lines 5-5 in FIG. 2;

FIG. 6 is a side elevational view of the film strip holder; and

FIG. 7 is an end view of the film strip holder.

DESCRIPTION OF THE PREFERRED EMBODIMENT

Referring now to the drawings, the linear film processing device of this invention is indicated generally at 10 in FIGS. 1 and 2, and includes a hollow elongated developer tube 11 which receives a film strip holder 12 (FIG. 6). The developer tube 11 external surface 13 on each end is provided with threads 14 (FIG. 5) for threadably receiving end caps 16 or 17. Each end cap 10 has an opening 18 formed therein and the internal surface 19 of the opening 18 is tapped to provide threads 21. Thus, it will be noted that the end caps 16 and 17 effectively seal both ends of the tube 11.

Internally provided in the tube 11 (FIGS. 3-5) is a chamber 22 that extends from substantially the bottom end 23 of the tube 11 for approximately three-fourths of the length thereof. The chamber 22 is kidney shaped in that it has two generally parallel curved sides which are connected at the top and bottom by two arcuate ends. A serpentine passage 24 fluidly connects on one end 26 to the upper end of the chamber 22 and is oval in cross section (FIG. 4). Fluidly communicating with the other end 27 of the serpentine passage 24 is a cylindrical passage 28. The upper end of the cylindrical passage extends to the top end 29 of the tube 11. The area of the tube around the serpentine passage 24 may either be integral with the tube 11 or it may comprise an insert element (not shown) which is disposed in the tube. However, the serpentine passage 24 is provided to form a light trap 25 thus preventing light from reaching the chamber when the end cap 17 is removed.

Secured to the outer surface of the tube 11 (FIGS. 1 and 5) is a handle 31 having a passage 32 formed axially therethrough. Spaced holes 33 and 34 are radially drilled through the tube 11 in alignment with the ends of the handle passage 32 thus providing fluid communication between the chamber 22 and the cylindrical passage 28.

Referring now to FIGS. 6 and 7, the film strip holder 12 is depicted as being arcuate in cross section with two inwardly facing flanges 36 and 37 secured to the edges thereof. The internal width between the edges is slightly smaller than the width of a film strip 38 (FIG. 7). Therefore upon mounting the film strip 38 in the holder 12 it will have a transverse bow thereon which projects toward the center of the holder 12. The length of the holder is at least as long as the length of the film strip and no longer than the length of the tube from the end cap 18 to the serpentine passage one end 26.

To provide easier insertion of the film holder 12 into the chamber 22 is a second cylindrical passage 39 which is formed in the bottom end of the tube 11 and which fluidly communicates with the chamber 22. The area 41 of the junction between the chamber 22 and the second passage 39 is beveled to eliminate any obstruction to the end of the film strip holder 12 as it passes from the second passage 39 into the chamber 22.

In operation, in total darkness a roll of exposed film 38 is removed from its reel or cartridge and one end thereof is grasped between the thumb and forefinger. The film strip holder 12 is grasped in the other hand with the open side face up. The one end of the film strip 38 is placed in the holder with the edges thereof disposed underneath the flanges 36 and 37 and the center of the strip bowed downwardly toward the closed side

of the holder. The one end of the strip is then slowly pulled along the channel formed by the flanges and the closed side until the strip lies fully in the channel. The resulting tension between the film strip edges and the internal walls of the holder retains the film in position within the channel. It will thus be noted in FIG. 7 that the film is disposed completely within the channel and neither side of the film contacts the holder nor can they touch the tube.

The film strip holder 12, now loaded with the exposed film strip 38, is inserted into the bottom end 23 of the tube 11 and the end cap 16 is threadably secured to the tube. It will be observed that the chamber 22 is only slightly larger than the holder 12 and is shaped to permit the holder to be inserted in only one manner, therefore it may be necessary to rotate either the holder or the tube to facilitate the loading.

Upon completion of the loading of the holder 12 in the tube 11 and the sealing of the bottom end 23 with the end cap 16 the device may be taken into a lighted area as the film 38 is protected by the light trap 25. The tube 11 is then charged with developer solution by pouring it into the cylindrical passage 28. The other end cap 17 is threadably mounted on the top end 29 of the tube 11 and the tube is inverted at regular intervals to agitate the solution. After a suitable time, prescribed by the manufacturer of the solution as determined by the concentration and temperature the end cap 17 is removed and the solution poured from the tube. Similar steps are taken with the bath solution, fixer solution and water, until the chemical processing of the film is completed. The film strip holder is then removed from the tube via the bottom end 23.

The hollow handle 31 opens on both ends of the light trap 25 and serves not only as a handle but as an internal air vent to allow the smooth flow of solutions through the light trap 25.

I claim:

1. A linear loading film processing device for developing an elongated strip of film, said film processing device comprising:

an elongated developer tube having a bottom end and a top end, said tube having a chamber formed longitudinally therein which has a lower end exiting the bottom end of said tube and an upper end disposed intermediate said bottom and top ends, said tube having a first cap removably mounted on the top end of said tube and a second cap removably mounted on the bottom end of said tube;

a light trap having opposed ends disposed in said tube adjacent the upper end of said chamber and having a serpentine passage formed longitudinally therethrough from one end to the other end thereof with the one end of said passage fluidly communicating with the upper end of said chamber;

a charging passage formed in the top end of said tube and having a first end fluidly communicating with the other end of said serpentine passage and a second end exiting the top end of said tube;

a film strip holder for holding film wherein the sides of the film do not contact the holder, said holder removably disposed in said chamber between said light trap and the bottom end of said tube, said holder being arcuate in cross-sectional view and having an inwardly facing flange secured to each edge thereof to form a channel with the internal width from edge to edge of the channel being

slightly smaller than the transverse width of the film thus causing the film strip to have a transverse bow projecting toward the center of the film strip holder; and

an interior air vent formed in said tube around said light trap and fluidly communicating with the upper end of said chamber and the first end of said charging passage.

2. A linear loading film processing device as defined in claim 1 and including a handle secured to said tube outer surface in alignment with said light trap, said handle having said interior air vent formed therethrough, and said tube having a pair of spaced holes formed radially therethrough for fluidly interconnecting said air vent with said chamber and said charging passage.

3. A linear loading film processing device as defined in claim 2 wherein said chamber is kidney shaped in cross-sectional view and its dimensions are only slightly greater than the dimensions of said film strip holder.

5 4. A linear loading film processing device as defined in claim 3 wherein the lower end of said chamber is enlarged and the inner wall of said tube at the juncture of said enlarged chamber and said kidney shaped chamber is beveled to eliminate any obstruction to the film strip holder as it is inserted into said chamber.

10 5. A linear loading film processing device as defined in claim 4 wherein said charging passage is enlarged to permit said passage to be charged with developing solution.
